LADY'S STOCKING

Arthur H. Rogers, Altamahaw, N. C., assignor to
Glen Raven Knitting Mills, Inc., Glen Raven,
N. C.

Application February 13, 1950, Serial No. 7,921

Term of patent 14 years

(Cl. D47—7)

To all whom it may concern:

Be it known that I, Arthur H. Rogers, a citizen of the United States, residing at Altamahaw, Alamance County, State of North Carolina, have invented a new, original, and ornamental Design for a Lady's Stocking, of which the following is a specification, reference being had to the accompanying drawing, forming a part hereof.

Fig. 1 is a side view in flattened condition of a lady's stocking showing my new design;

Fig. 2 is a fragmentary perspective view thereof as it appears when worn, and

Fig. 3 is a fragmentary underside perspective view thereof as it appears when worn.

I claim:

The ornamental design for a lady's stocking, as shown.

ARTHUR H. ROGERS.
